SANITARY HAIR COVER

Judith Gordon, Brooklyn, N. Y.

Application October 24, 1936, Serial No. 107,440

3 Claims. (Cl. 2—174)

This invention relates to new and useful improvements in a sanitary hair cover.

The invention has for an object the construction of a hair cover which is formed from a sheet 5 of material and which may be readily and conveniently engaged upon one's head.

Specifically, the invention proposes to protect the hair while the face is exposed so that creams may be applied to the face without soiling the 10 hair, also to protect the hair from the sun and sand on beaches.

Still further the hair cover may be used for general household purposes to protect the hair during cleaning of the home.

15 Another one of the objects is the provision of pliable elements arranged upon the hair cover in a manner so that it is capable of holding the hair cover at various sizes to fit the heads of different people.

20 Another one of the objects of this invention is the provision of an eyelet adapted to coact with said pliable means for holding the top portion of the hair cover in position.

25 Still further the invention proposes the construction of an article as mentioned which is simple and durable and which may be manufactured and sold at reasonable cost.

30 For further comprehension of the invention, and of the objects and advantages thereof, reference will be had to the following description and accompanying drawing, and to the appended claims in which the various novel features of the invention are more particularly set forth.

35 In the accompanying drawing forming a material part of this disclosure:—

Fig. 1 is an elevational view of a sanitary hair cover constructed according to this invention.

Fig. 2 is a pictorial view of the hair cover partially applied on a wearer.

40 Fig. 3 is a rear view of Fig. 2.

Fig. 4 is a fragmentary horizontal sectional view taken on the line 4—4 of Fig. 3.

Fig. 5 is a fragmentary perspective view of the left hand end of Fig. 1.

45 Fig. 6 is a view similar to Fig. 3 but showing the hair cover completely applied.

Fig. 7 is a front elevational view of Fig. 6.

The sanitary hair cover, according to this invention, comprises a sheet of material having a central portion 10 consisting of an edge section 10^a to engage against one's brow and a top section 10^b extending upwards from the edge section into a point. This top section is formed with an opening 11. An eyelet 11' engages upon 50 the material around this opening for reinforcing

it. The sheet material continues at the side into narrow end portion 12 for extending around one's head to the back. A pliable member 13 is transversely mounted at its center upon one of said end portions 12 and is adapted to form a core about which the ends of said end portions may be wound when the hair cover is engaged on one's head, as clearly shown in Fig. 4. This pliable member 13 has end portions 13^a bendable together, as shown in Fig. 3, for holding the end portions of the hair cover.

5 10 15 The pliable member 13 comprises an outer casting of paper housing an internal wire 13^b. One end portion 13^a is formed with a reduced section 13^c forming shoulders 13^d for the purpose hereinafter further described. The pliable member 13 is shown attached upon the end portion 12 by several staples 15.

15 20 The sanitary hair cover is engaged upon one's head in the following manner: The edge portion 10^a is first engaged across the brow with the pointed portion extending vertically upwards. The end portions 12 are bent around the head to the back and the excess is wound up about the pliable member 13 as a core. Thus the hair cover is capable of fitting heads of different sizes.

25 30 35 Each of the end portions are wound up so that the hair cover is tight on one's head and the ends 13^a of the pliable member are bent outwards and towards each other as shown in Fig. 3. This will serve to hold the end portions 12 in fixed positions. The pointed portion of the protector is bent down across the top of the head and the eyelet 11' engaged upon the reduced section 13^c so that the eyelet rests against the shoulder 13^d. The hair cover is then completely mounted on one's head.

40 While I have illustrated and described the preferred embodiments of my invention, it is to be understood that I do not limit myself to the precise constructions herein disclosed and the right is reserved to all changes and modifications coming within the scope of the invention as defined in the appended claims.

45 Having thus described my invention, what I claim as new, and desire to secure by United States Letters Patent is:—

1. A sanitary hair cover comprising a sheet of material having a central portion consisting of an edge section to engage against one's brow and a top section extending upwards and formed with an opening, narrow end portions extending from said central portion for extending around one's head to the back, and a pliable member transversely mounted upon one of said end portions 50 55

and adapted to form a core about which the ends of said end portions may be wound and having portions bendable together to hold said latter end portions, whereby said top section may be 5 bent backwards and its opening engaged on one of the bent ends of said pliable member.

2. A sanitary hair cover comprising a sheet of material having a central portion consisting of an edge section to engage against one's brow and 10 a top section extending upwards and formed with an opening, narrow end portions extending from said central portion for extending around one's head to the back, and a pliable member transversely mounted upon one of said end portions 15 and adapted to form a core about which the ends of said end portions may be wound and having portions bendable together to hold said latter end portions, whereby said top section may be bent backwards and its opening engaged on one of the 20 bent ends of said pliable member, said pliable member comprising a casing of paper and an internal wire.

3. A sanitary hair cover comprising a sheet of

material having a central portion consisting of an edge section to engage against one's brow and a top section extending upwards and formed with an opening, narrow end portions extending from said central portion for extending around one's head to the back, and a pliable member transversely mounted upon one of said end portions and adapted to form a core about which the ends of said end portions may be wound and having portions bendable together to hold said latter end portions, whereby said top section may be bent backwards and its opening engaged on one of the bent ends of said pliable member, the end portion of said pliable member which engages through said opening being formed with a 15 reduced portion engaging through said opening, said reduced portion forming a shoulder, which abuts against the material around said opening to fixedly hold said top section in position between said shoulder portion and the bent portion 20 of said pliable member.

JUDITH GORDON.
